(22) Filed: **Jun. 17, 2002**

CLAIM

(30) **Foreign Application Priority Data**

The ornamental design for network concentrator, as shown and described.

Feb. 27, 2002 (JP) 2002-004889

(51) LOC (7) Cl. **14-03**

DESCRIPTION

(52) U.S. Cl. **D14/242**

This object is used for collecting telephone wires from a plurality of VDSL modem to a network.

(58) Field of Search D14/240, 242; 379/957; 455/508, 510, 524; 439/717; 220/4.02

FIG. 1 is a front elevational view of a network concentrator showing our new design;

(56) **References Cited**

FIG. 2 is a rear elevational view thereof;
